(57) **CLAIM**

The ornamental design for a cooking pan for a kettle grill, as shown and described.

DESCRIPTION

FIG. 1 is a perspective view of the cooking pan of the invention for use in a kettle grill.

FIG. 2 is a top view of the cooking pan, and illustrating for purposes of reference a position of the pan on a grate within the kettle grill wherein the grate shown in dotted lines does not comprise any part of the invention claimed herein; and, FIG. 3 is a side elevation view of the cooking pan.

The cooking pan is intended to be positioned on a grate in a kettle grill and to hold and contain food to be cooked in the grill.
